UNITED STATES PATENT OFFICE.

JOHN DENCKER, OF MANITOWOC, WISCONSIN.

DESIGN FOR A COMBINATION-TOOL.

54,308.

Specification for Design.

Patented Dec. 23, 1919.

Application filed September 8, 1919. Serial No. 322,562. Term of patent 14 years.

To all whom it may concern:

Be it known that I, JOHN DENCKER, a citizen of the United States, residing at Manitowoc, in the county of Manitowoc and State of Wisconsin, have invented a new, original, and ornamental Design for Combination-Tools, of which the following is a specification, reference being had to the accompanying drawing, forming part thereof.

In the drawings—

Figure 1 is a side elevation of a combination tool, showing my new design;

Fig. 2 is a rear elevation thereof;
Fig. 3 is a top plan view of the tool, and
Fig. 4 is a cross-section taken on line 4—4
of Fig. 1.

I claim:

The ornamental design for a combination tool, as shown.

In testimony that I claim the foregoing I have hereunto set my hand at Manitowoc, in the county of Manitowoc and State of Wisconsin.

JOHN DENCKER.
